(57) **CLAIM**

The ornamental design for a Vitom 3D telescope, as shown and described.

DESCRIPTION

FIG. 1 is a top, front and left side perspective view of a Vitom 3D telescope in accordance with the new design;

FIG. 2 is a top perspective view thereof;

FIG. 3 is a bottom perspective view thereof;

FIG. 4 is a left side perspective view thereof;

FIG. 5 is a right side perspective view thereof;

FIG. 6 is a front perspective view thereof; and,

FIG. 7 is a rear perspective view thereof.

The broken lines in FIGS. 1, 6 and 7 represent the bounds of the claimed design and form no part of the claimed design. The “Vitom” title forming part of the claimed design is a registered trademark, Registration No. 3585361, of Karl Storz GmbH & Co. KG.
